(57) **CLAIM**

The ornamental design of a sterilizable battery component, as shown and described.

DESCRIPTION

FIG. 1 is a pictorial view of the sterilizable battery component of this invention;

FIG. 2 is a top view of the sterilizable battery component of FIG. 1;

FIG. 3 is a bottom view of the sterilizable battery component of FIG. 1;

FIG. 4 is a right side view of the sterilizable battery component of FIG. 1;

FIG. 5 is a front view of the sterilizable battery component of FIG. 1; and,

FIG. 6 is a back view of the sterilizable battery component of FIG. 1.

The left side of the sterilizable battery component of this invention is a mirror image of the right side, illustrated in FIG. 4 herein; therefore, an illustration of the left side is not needed.
